Primary Examiner — Clare E Heflin(74) *Attorney, Agent, or Firm* — Cooper & Dunham, LLP(57) **CLAIM**

The ornamental design for a landscape light, as shown and described.

DESCRIPTION

FIG. 1 is a front perspective view of a landscape light in accordance with the present design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines are for illustrative purposes only and form no part of the claimed design. The shading represents contour of the claimed design.
